UNITED STATES PATENT OFFICE.

CHARLES E. GREENLIEF, OF NEWTON, IOWA.

GEAR MECHANISM FOR WASHING-MACHINES.

1,179,092.

Specification of Letters Patent. Patented Apr. 11, 1916.

Application filed March 23, 1912. Serial No. 685,748.

To all whom it may concern:

Be it known that I, CHARLES E. GREENLIEF, a citizen of the United States, residing at Newton, in the county of Jasper and State of Iowa, have invented new and useful Improvements in Gear Mechanism for Washing-Machines, of which the following is a specification.

It is the object of my present invention 10 to provide a gear mechanism whereby the movable elements of a washing machine may be driven from a suitable motor or motive device, and whereby a wringer mounted on the machine may be started, stopped, or reversed at the will of the operator, the several parts of the gearing being grouped compactly and insuring a positive and reliable action as hereinafter set forth more in detail.

In the accompanying drawings, forming 20 a part of this specification, Figure 1 is a side elevation of the complete machine, one of the legs being broken away to expose the gear box. Fig. 2 is an end elevation of the structure shown in Fig. 1. Fig. 3 is a detail 25 of the upper or socket end of the driving rock lever. Fig. 4 shows the gear box with its cover removed and its gears exposed. Fig. 5 is a sectional view in elevation through the structure shown in Fig. 4. Figs. 30 6 and 7 are transverse sections through different parts of the gear box.

In the construction shown, a wash tub 1 mounted on legs 2 carries a wringer 3 and serves as a support for the gear mechanism 35 hereinafter claimed. This tub is equipped with the usual agitator or dolly mounted at the center of the tub on a vertical shaft which periodically reverses in direction and is driven in the usual manner by a trans- 40 versely movable rack bar 4.

A vertical rock lever 5 is pivotally mounted to the slide of the tub at a bracket 6 and at its upper end is pivotally connected with the rack bar 4, the upper end of the 45 rock lever being cut away at 7, as shown in Fig. 3, so that the rack bar can be swung backward away from the tub as shown by dotted lines in Fig. 1. Integral with the top end of lever 5 is a socket 8 having bolt 50 holes for receiving the end of a temporary wooden handle in case, for any reason, the machine is to be driven by hand instead of by motor. The lower end of the rock lever 5 is pivoted to a link 9 which engages and 55 is driven by a crank 10, carried by a solid and relatively heavy disk 11 mounted in a

vertical plane and secured to a transverse drive shaft 12 at the other end of which is a beveled driving gear 13.

The main driving gears for the washing 60 machine are located in a gear box 14, preferably of cast iron and of fluid tight construction at the bottom, this box being provided with a flat removable cover, fitting closely thereover. A counter-shaft 15 ex- 65 tends through said gear box from end to end and is supported in suitable bearings 16 and 17 at the respective ends of the box. Outside of bearing 17 and rigidly mounted on counter-shaft 15 is a sprocket wheel 18 70 whereby a sprocket chain may be driven for rotating the roll shaft 19 of the wringer. This counter-shaft 15 also carries a rigidly mounted spur gear 20 and a similar but smaller spur wheel 21, also rigidly connected 75 to the counter-shaft 15. These are the gears used for driving the wringer, the smaller one being used for the reverse drive, as hereinafter set forth more in detail.

Loosely mounted on counter-shaft 15 is 80 a spur gear 22, one face of which is formed into a bevel-gear 23, having driving connection with the bevel gear 13 whereby the transverse shaft 12 and the washing mechanism is driven. A pulley 24 mounted on 85 the outer end of a drive shaft 25 serves as the outer end of a drive shaft 25 serves as a means for driving a small pinion 26 which is splined to the drive shaft, but is movable along said shaft so that it can be brought successively into engagement with the various gears of said box. As a means for effecting this shifting of the pinion along its axis, there is provided a bracket 27 operatively connected with a guide bar 28 carried in suitable bearings 29 and 30 when 90 the pinion 26 is shifted from one driving position to another. A small counter-gear 31 is mounted below gear 21 in position to mesh with pinion 26 to effect reversal of the wringer when said pinion is at the extreme 95 outer limit of its movement. The driving engagement, under these conditions, is illus- 100 trated in Fig. 7.

Fig. 4 shows the pinion 26 in mesh with gear 20, this being the normal driving position for the wringer. When pinion 26 is in mesh with spur gear 22, the washing mechanism is driven, gear 22 turning freely on countershaft 15 and leaving gears 20 and 21 stationary. At a position intermediate 110 between gears 22 and 20, the pinion 26 will will be out of mesh and can rotate freely

without driving either the washing machine or the wringer. As a means for shifting the driving pinion 26 along its axis to change its driving engagement within the gear box, 5 I make use of a link 32 pivotally connected with a stud 33 which is rigidly connected with the bracket 27 and slides in a slot or guide-way in the top of the gear box. Link 32 is pivotally connected to the inturned 10 arm 34 of a vertical control shaft 35 suitably mounted adjacent to the wringer drive and carrying a handle 36 whereby it may be rocked at the will of the operator to throw the washing mechanism in or out of gear 15 and to start the wringer in either direction or to stop it as desired. The gear box 14 and its inclosed gears are supported from the legs of the tub by suitable brackets or cross bears 37. The gear box may contain oil 20 for lubrication of the gears and serves to protect the gears from injury.

I claim:—

1. In a gear mechanism for washing machines the combination of a support, a drive 25 shaft, a counter-shaft at the side thereof, a crank shaft transverse to said counter-shaft, a driven shaft, a reciprocating connection operatively connected with said driven shaft and said crank shaft, a spur gear mounted 30 on said counter-shaft and having driving connection with said crank shaft, and a pinion driven by said drive shaft and slideable along the axis thereof into and out of engagement with said spur gear.

2. In a gearing mechanism for washing 35 machines, the combination of a crank shaft, a reciprocating element operatively connected to said shaft and driven thereby, a counter-shaft, a spur gear mounted to freely 40 turn on said counter-shaft and having a driving connection with said crank shaft, a pinion, means for driving said pinion and adjusting means for shifting said pinion into and out of engagement with said spur 45 gear to start or stop the movement of said reciprocating element.

3. In a washing machine gearing, the 50 combination of a support, a shaft mounted on said support and movable with a reciprocating motion, reciprocating elements operatively connected to move said shaft, a crankshaft connected to move said reciprocating elements, a bevel gear carried by said 55 crank shaft, driving means for said gear, said means including a spur gear, a pinion, and means for driving said pinion, said pinion being movable parallel to the axis of said spur gear into and out of driving engagement with said spur gear.

4. In a gear mechanism for washing 60 machines, the combination of a drive shaft, a counter-shaft arranged parallel thereto, a pinion mounted on said drive shaft and slideable along the axis thereof, a pinion mounted 65 to turn freely on said counter-shaft and

having a beveled face with gear teeth, a crank shaft mounted transversely to said counter-shaft, a bevel gear carried by said crank shaft and in position to be driven by the beveled face of said spur gear, and reciprocating elements carried by said support and operatively driven by said crank shaft. 70

5. In a gear mechanism for washing machines the combination of a support, a reversely rotatable vertical shaft carried by 75 said support, reciprocating means for driving said shaft, a gear mechanism for actuating said reciprocating means, said gear mechanism including a transverse shaft, a bevel gear carried by said transverse shaft, 80 a counter-shaft, a combined bevel and spur gear freely rotating on said counter-shaft, a drive shaft, and a pinion slideable on said drive shaft into and out of engagement with said spur-gear. 85

6. In a washing machine gearing the combination of a support, a drive shaft and a counter-shaft mounted below said support, a crank shaft mounted transversely to said counter-shaft, a beveled gear carried by said counter shaft, a pair of gear wheels mounted on said counter-shaft, a third gear wheel carried by said counter-shaft and free to turn thereon, said last named gear having driving engagement with said beveled gear, a counter-gear in mesh with one of said spur gears, a pinion rotated by said drive shaft and movable along the axis thereof into and out of driving engagement with the other gears, and a gear box inclosing all of said 90 gears. 95

7. In a gear mechanism for washing machines, the combination of a support, a vertical reciprocating shaft carried by said support, reciprocating elements for driving said shaft, a crank shaft operatively connected to move said reciprocating elements, a counter-shaft mounted below said support, a bevel gear carried by said counter-shaft, means for operatively connecting said bevel gear with said reciprocating elements, a drive shaft mounted below said support and parallel to the counter-shaft, a pinion slidably mounted and connected to said drive 100 shaft, a spur gear carried by said bevel gear, a slidably mounted bracket carried by said pinion, a link pivotally connected to said bracket, and a control shaft connected to said link whereby the said pinion may be thrown into and out of mesh with the said 105 spur gear. 110

8. In a washing machine gearing, a support a driven shaft, a reciprocatory member operatively connected to said driven shaft, a driving shaft, a counter-shaft, a crank shaft positioned transversely to the counter-shaft and connected to said reciprocatory member, and means for operatively connecting the drive shaft with the counter shaft for the purpose specified. 115 120 125 130

9. In a washing machine gearing, the combination of a support, a driven shaft therein, a reciprocatory member for driving said driven shaft, a drive shaft, a counter shaft arranged parallel thereto, a gear carried by the counter shaft, a crank shaft operatively connected to said gear and operating said reciprocatory member, means carried by the drive shaft whereby the same may be thrown 10. into and out of operative engagement with the gear for the purpose specified.

10. In a washing machine gearing, the combination of a support, a drive shaft, a crank shaft arranged transversely thereto, 15 gearing connected to said crank shaft, a pinion slidably mounted upon the drive shaft and adapted to operatively connect and disconnect the drive shaft and the crank shaft through said gearing, means for shifting said pinion substantially as described, a driven shaft and a reciprocatory connection from said crank shaft thereto.

11. In a washing machine gearing, the combination of a drive shaft, a counter shaft arranged parallel thereto, a spur gear carried by the counter shaft, a crank shaft arranged transversely to the counter shaft and being operatively connected to the spur gear, a pinion slidably mounted on the drive 25

shaft and adapted to mesh with said gear on the counter shaft for operatively connecting the spur gear with the drive shaft, a vertical control shaft, and a link connecting said vertical control shaft with the pinion whereby the latter will be thrown into and 30 out of mesh with the spur gear.

12. In a washing machine gearing, the combination of a drive shaft, a counter shaft arranged parallel thereto, a spur gear carried by the counter shaft, a crank shaft positioned transversely to the drive shaft and operatively connected to the spur gear, a guide bar, a bracket carried by the guide bar, a pinion keyed to and slidably mounted upon drive shaft, a connection between the 40 said bracket and pinion, a control shaft, means for operatively connecting the control shaft with the bracket whereby the pinion will be thrown into and out of engagement with the spur gear for the purpose 45 specified.

In witness whereof, I hereunto subscribe my name to this specification in the presence of two witnesses.

CHARLES E. GREENLIEF.
